BASEBALL GAME

Walter F. Lipchow, Milwaukee, Wis.

Application January 9, 1937, Serial No. 119,809

1 Claim. (Cl. 273—105)

This invention appertains to games and game apparatus, and more particularly to a novel game embodying the elements of baseball, and one in which the skill or marksmanship of a player forms an important part.

One of the primary objects of the invention is to provide a game-board having the simulation of a baseball field thereon toward which counters are adapted to be tossed by the players, the game-board having a series of pockets or openings therein for the counters, the counters, when entering the pockets or openings or when hanging on the walls thereof, constituting certain plays of baseball, whereby a realistic parlor game of baseball will be had in which the physical skill of the players forms an important feature.

Another salient object of the invention is to provide a baseball game embodying a game-board having a series of counting openings therein, and a series of pockets below the openings for the reception of the counters, when the counters are not played in the openings, the pockets also counting certain plays of baseball, such as fouls, balls, and strikes.

A further object of the invention is the provision of a chute for receiving the counters played in the openings, and manual means for permitting the counters played in the pockets to fall in the chute, whereby all of the counters can be conveniently recovered after a player has had his turn.

A still further object of the invention is to provide a baseball game of the above character, of simple and durable construction, which can be manufactured and placed upon the market at a reasonable cost.

With these and other objects in view, the invention consists in the novel construction, arrangement, and formation of parts, as will be hereinafter more specifically described, claimed, and illustrated in the accompanying drawings, in which drawings:

Figure 1 is a fragmentary front elevation of the improved game-board.

Figure 2 is a fragmentary, detail sectional view illustrating the manually operated gate for permitting the counters played in the pockets at the bottom of the board to fall in the receiving chute.

Figure 3 is a longitudinal section through the novel game-board, taken substantially on the line 3—3 of Figure 1, looking in the direction of the arrows.

Figure 4 is a fragmentary side elevation of a game-board showing the lower end thereof and

illustrating the means for manually operating the gate.

Referring to the drawings in detail, wherein similar reference characters designate corresponding parts through the several views, the letter B generally indicates the novel game-board, which forms an important feature of the present invention.

This game-board B comprises a top playing board 5 on which is adapted to be painted or otherwise affixed the simulation of a baseball field. Hence, the outer surface of the playing board has formed thereon a diamond 6, the four corners of which represent bases, and the board in the four corners has openings 7 formed therein. The lines forming the lower sides of the diamond are continued to simulate foul lines 8. The infield defined by the diamond has formed therein a plurality of openings 9, which can be of different sizes, and the outfield defined by the diamond has also formed therein a plurality of openings 10, which are also of different sizes. The part of the board inward or below the diamond and foul lines 8 has also formed therein a plurality of openings 11, which can be of different sizes.

Suitable top and side walls 13 and 14 are provided for the playing board, and the top wall can carry a backstop or sign plate 15, which can carry the rules of the game or the plays which the various openings represent.

Connected to the side walls 14 in spaced relation to the playing board 5 is a front wall 16, a part of which, at least, is formed of glass or other transparent material. The space between the lower or front edge of the playing board 5 and the front wall 16 is normally closed by a hinged flap or gate 17.

A series of equidistantly spaced partitions 18 are disposed in rear of the wall 16, so as to form 40 in conjunction with the wall 16, the gate 17 and a part of the playing board 5, a series of pockets 19.

In rear of the playing board 5 is a guide board 20, which forms a chute for guiding counters 21 45 played through the openings in the board toward the front lower end of the board, and the front edge of the guide wall 20 can be angled forwardly and downwardly below the gate 17.

Counters played in the pockets 19 can be automatically dropped into the chute or onto the guide wall after a player has finished his turn by manually operating the gate. Any desired means can be provided for operating or tripping the gate, and, as illustrated, a bell-crank lever 55

22 is provided, and the same is pivoted at its angle to the game-board, as at 23. The lower short arm of the lever has its forward end provided with a pin 24, which extends through an arcuate slot 25 formed in the game-board. This pin is connected to the gate adjacent to the forward end thereof, and a contractile coil spring 26 is employed for normally holding the short arm of the lever, and consequently the gate in a raised position. The terminals of the contractile coil spring 26 are connected respectively to the pin and to the game-board.

The outer end of the long arm of the lever has secured thereto a pull cord 27, and obviously by pulling upon this cord the bell-crank will be actuated for lowering the gate 17 against the tension of the spring 26.

The playing board can have marked thereon above each opening suitable indicia, so as to indicate to a player what a counter constitutes when the same is thrown through an opening or hangs on the wall of the opening. Likewise, the board can have marked above the pockets 19 the plays which the pockets represent, or the plays a counter represents when the same hangs on the walls of the pockets.

In Figure 1 initials have been placed above the openings and pockets to indicate the various plays, and by referring to the schedule below, the meaning of the initials can be easily determined:

	Ball goes through	Ball hangs
35		
H. F.	High fly-out.....	Single on error.
T.	Triple.....	Out at third. Other runners score.
T. S.	Triple steal (bases must be loaded).	Runner trying score is out at home.
H. R'.	Home run.....	Foul—Strike.
H. R.	Home run.....	Out at home.
S. 2.	Steals second base (only if man is on first base).	Out at second base.
D. S.	Steals home and second (man on first and man on third only).	Out at home—safe at second.
S. F.	Sacrifice fly—batter out—runner advance one base.	Out—no advancement for runner on base.
45		
D.	Double.....	Out.
T. P.	Triple play.....	Two men nearest home are out.
L. D.	Line drive—out.....	Out.
L. S.	Long single—runners advance two bases.	Runners on bases advance only one base.
50		
S. H.	Steals home.....	Caught at home—out.
L. D'	Long double—all runners on base score.	Runners on base advance only two bases.
D. P.	Double play—two outs.	One out only. Batter safe on first.
D'.	Double.....	Fielder's choice—one out.
S.	Single—runner on second "sleeping."	Runner on second does not advance but is safe.
55		
S. 3.	Steals third (only if man on second).	Out at third.
S. S.	Short single.....	Out.
F. F.	Foul fly.....	Out.
D. S'	Double steal (man on third to home and man on second to third).	Runner out at home.
60		
P. O.	Popout.....	Out.
S. P.	"Squeeze" play (only a man on third).	Runner out at home. Batter safe on first. Out at second trying to "stretch."
D. S"	Double steal (runners to second and third safe).	Runner out at third.
W. P.	Wild pitch—All runners advance one base—if no runners on base—out.	"Balk"—all runners advance one base—if no runners on base—batter goes to first on error.
65		
F. F'	Foul fly—out.....	Strike (fielder dropped ball)—error.
P. P.	Purposely passed (runner on third only).	Batter out.
70		
P. P'	Purposely passed (runners on first and second).	Batter out.

	Ball goes through	Ball hangs
S. B.	Sacrifice bunt (at least one base must be loaded).	No advance if man is on first—force-out.
B.	Bunt—batter safe on first.	No advance—if no runner on base, batter out. 5
W. T.	Wild throw. All runners advance one base.	Batter out.
P. P"	Purposely passed—runners on second and third.	Batter out.
P. P'''	Purposely passed—runners on first and third.	Batter out.
B'	Bunt (if runner on third—out)—batter safe.	Runner back safe on third—batter out. 10
B. H.	Batter hit (runner on third caught trying for home).	Popout.

The counters 21 are in the nature of small bags filled with granular or powdered material, such as blasting sand, and obviously if the counters are not properly played the same will hang on the walls of the openings and pockets.

All of the openings are so arranged that groups of openings constituting strikes, files, etc., will be around an opening counting base hits and the like. Thus, a player whose aim is not perfect and who tosses for a particular pocket which constitutes a run or a hit is liable to have his counter enter an opening which constitutes a fly, a strike, or a putout. Thus, this adds considerable interest to the game.

In playing the game, it is desirable that sides be chosen, and any number of persons can play on the sides. In order to more closely simulate a regular baseball game, it is proposed that there be nine players on each side. The players take their turns in regular order, and the counters are tossed underhand toward the playing board. The players can stand any desired distance from the board, say, about twenty-five feet.

As all of the plays in the game of baseball are represented on the playing board, the game can be played in exactly the same manner as a regular game of baseball.

It is preferred to have a person not taking part in the actual playing of the game to act as the umpire, and this person can keep account of the plays and the score and can also actuate the gate 17.

Changes in details may be made without departing from the spirit or the scope of this invention, but what I claim as new is:

A game apparatus comprising, a playing board arranged at an angle to the vertical, having the simulation of a baseball field thereon and a series of openings therein, a backboard extending entirely under the playing board and arranged in spaced parallel relation to the playing board defining a runway in conjunction therewith, counters adapted to be tossed toward the board and played into the openings, the backboard guiding the counters played through said openings toward the lower front end of the playing board for reuse, a series of pockets disposed at the lower end of the playing board and in spaced relation thereto for receiving counters failing to pass through the openings, the bottoms of the pockets being open and disposed above the backboard, a pivoted gate normally closing the bottom of all of said pockets, and manual means for operating the gate at a point remote from the playing board for permitting the discharge of counters from said pockets into the runway and on the backboard.

WALTER F. LIPCHOW. 70
